UNITED STATES PATENT OFFICE.

JOEL R. LEWIS, OF YOUNGSTOWN, OHIO, ASSIGNOR OF ONE-FOURTH TO JOHN W. DAVIS,
OF YOUNGSTOWN, OHIO.

LIQUID-FEEDING DEVICE.

1,285,256.

Specification of Letters Patent. Patented Nov. 19, 1918.

Application filed April 15, 1918. Serial No. 228,735.

To all whom it may concern:

Be it known that I, JOEL R. LEWIS, citizen of the United States, residing at Youngstown, in the county of Mahoning and State of Ohio, have invented certain new and useful Improvements in Liquid-Feeding Devices, of which the following is a specification.

This invention relates to certain improvements in liquid feeding devices for use particularly in supplying liquid fuel to internal combustion engines of automobiles and the like, in connection with which it is very often desirable to have the primary fuel tank carried on the vehicle at a level below the carburetor.

The object of the invention is to provide a device of simple construction, economic of manufacture and highly efficient in automatic operation with particular relation to the construction of the vacuum tank portion thereof, to which the liquid fuel is elevated as by the suction of the engine, and intermittently discharged therefrom to be fed by gravity to a vaporizing device, as for instance, to the float chamber of a commercial carburetor.

Other objects and advantages relate to the detail of construction of the vacuum tank as will hereinafter appear from the following description, taken in connection with the accompanying drawings, in which—

Figure 1 is a somewhat diagrammatic view of the liquid feeding device assembled with a low level fuel tank and a carburetor and manifold for combustion engine, the auxiliary tank being in cross section and somewhat enlarged in order to show detail.

Fig. 2 is a perspective view of top of vacuum tank showing float and connections.

Fig. 3 is a detail view in cross section of valves.

Fig. 4 is a detail of combination valve piston.

As shown, the invention comprises a vacuum tank 1 having suitable connections through a fuel pipe 2 with a primary fuel tank 3, a second connection, as through suction pipe 4, with any source of suction,

as the manifold 5 of the engine, and a third connection as through pipe 6 with a carburetor 7.

The invention herein centers about the construction of a vacuum tank 1 which comprises a sheet metal tubular body portion 8 preferably cylindrical in form and having its lower end closed by end wall 9 and divided into two chambers 10 and 11. As indicated in Fig. 1 these two chambers 10 are constituted as two separate cups or vessels, each opening upwardly. The outer chamber 11 is considerably longer and deeper than the inner chamber 10 and sufficiently larger in diameter to leave space for an inturned flange 12 at its brim. The upper and inner chamber 10 is provided with a cover portion 13 provided with openings 14 near its circumference in order that it may be bolted or fastened to the inturned flange 12.

Underneath this cover portion 13 is fastened by any means the chamber 10. The cover portion 13 is provided with a fuel intake opening connected by the pipe 2 with the supply tank 3 as shown in Fig. 1, another opening connected by a pipe 4, with the intake manifold 5 of an engine and a third opening fitted with a vent pipe 15 communicating with the open air.

It should be understood that the pipes 4 and 15 are controlled by valve-seats 16 and 17 respectively, which are so controlled by a common piston valve 18 that they can only open alternately. See Fig. 3. When the piston valve seat 16 is open, and the piston valve seat 17 is closed, the engine suction is permitted to effect a reduction of pressure within the chamber 10 thus causing a flow of fuel through the pipe 2 into the vessel and causing the float 19 to rise. The float 19 is connected, however, by a trip lever 20 and fulcrumed at point 21 to the end of a downwardly extending support lug 22. At the outer end of the trip lever 20 at point 23 there is attached a tension spring 24 whose opposite end is connected to the outer end of a trip lever 25 which in turn is fulcrumed at a point 26 being supported by a downwardly extend-

ing lug 27. Trip lever 20 has an upturned arm 28 formed to engage a stop 29 formed upon the lug 27.

By referring to Fig. 1 it will be seen that the float 19 has by its buoyant force caused by the incoming liquid, been sufficient to overcome the effect of the spring 24 and has raised the point 28 of the trip lever 20 above the fulcrum 21, and above the fulcrum 26 of trip lever 25 thereby causing the trip lever 25 to rise suddenly to its upper limit of movement causing the arm 30 to throw the piston of valve 18 against the valve seat 17.

By referring to Fig. 4 it will be seen that the arm 30 engages in the notch 31 of the valve piston 18.

By referring to Fig. 3 it will be seen that when the piston valve 18 is closed the air valve seat 17 is opened. The suction of the engine is now cut off and atmospheric pressure within the chamber 10 has been restored. This permits the fuel accumulated in the chamber 10 to flow downwardly into the chamber 11 past the flap valve 22 and from the chamber 11 it will flow by gravity through the pipe 8 to the carburetor 7. When the majority of the fuel has passed from the chamber 10 to the chamber 11 the buoyant force being thus removed from the float 19 the latter will fall to its lower limit which is determined by the engagement of stop 29 with the upturned arm 28 of the trip lever 20. To insure the free flow of the liquid from the chamber 11, however, it is essential that this chamber have communication with the atmosphere at all times and in the present construction this is afforded through the air intake pipe 33 which is fitted to a "T"-fitting 34 whose stem 35 is open to the air. The other arm of the "T"-fitting 34 is coupled to the pipe 16.

It will be understood by referring to Fig. 3 that when the trip lever 25 is acted upon by the coil spring 24 the piston valve-seats 16 and 17 will be opened alternately. The valve-seats 16 and 17 are each formed by an inturned lug 36 provided with a cup-shaped end formed to fit the end of the piston valve 18.

By referring to Fig. 3 it will be seen that these lugs 36 have a central opening at the bottom of the cup shaped portion extending in a short distance and then extending outwardly at right angles to the circumference of said lug, the downwardly extending portions 37 being provided with openings 38 so as to communicate with the valve seats 16 and 17.

Fig. 3 shows the piston valve seats 17 open and piston valve seats 16 closed. It will be noticed that in my device I have provided a double means of seating valve, namely, by the end of piston valve 18 fitting into the

cup end of lug 36 and by means of the 66 piston valve 18 fitting into the bore 40 directly in front of the cup shaped end of lug 36.

What I claim is:

1. In a device of the class described, a primary fuel tank, an auxiliary tank located above primary tank, a fuel pipe connecting said tanks, a fuel pipe leading from bottom of auxiliary tank to a carburetor, a cover plate covering top of the auxiliary tank, two piston valves located underneath said cover plate and diametrically opposite, a vent pipe leading from one valve, a suction pipe leading from the other valve to a manifold of gas engine, a common valve piston, two trip levers fulcrumed upon two downturned arms of cover plate, a coil spring tensioned between the outer ends of said trip levers, a float attached to arm of one of said levers, substantially as described for the purpose set forth.

2. In a device of the class described, the combination of a primary fuel tank, an auxiliary tank located above the primary tank, a fuel pipe connecting said tanks, a fuel outlet pipe leading from bottom of auxiliary tank to a carburetor, a cover plate fastened to the top of auxiliary tank, two piston valves located diametrically opposite and attached underneath said cover plate, a vent pipe leading from one of said valves, a suction pipe leading from the other valve to a manifold of gas engine, a common piston valve engaging the seats of said valves, two trip levers fulcrumed upon two downturned arms of said cover plate, an upturned arm of one of said trip levers engaging the common valve piston, a coil spring tensioned between the outer ends of said trip levers, a float attached to arm of one of said trip levers, substantially as described for the purpose set forth.

3. In a device of the class described, the combination of a primary fuel tank, an auxiliary tank located above the primary tank, a fuel pipe leading to the auxiliary tank, said auxiliary tank having two chambers one chamber of which extending into the upper portion of a second chamber, a cover plate fitting over upper chamber, two piston valves located underneath said cover plate and diametrically opposite each other, a vent pipe connected to one of said piston valves, a suction pipe connected to the other piston valve, two downwardly extending lugs positioned nearly opposite each other and near the circumference of the cover plate, trip levers fulcrumed from said downturned lugs, a coil spring attached to outer ends of said trip levers, a float attached to central portion of one of said trip levers, an upturned arm of said lever, a stop to engage said arm positioned upon side of the down-

turned lug, a cup-shaped valve seat, channels at bottom of said cups and extending out to their circumference, a notch formed at center of the common valve piston to engage the 5 upturned arm, a common valve piston formed with ends rounded, substantially as described for the purpose set forth.

In testimony whereof I affix my signature in the presence of two witnesses.

JOEL R. LEWIS.
